UNITED STATES PATENT OFFICE.

WALTER H. HART, OF NEW BRITAIN, CONNECTICUT, ASSIGNOR TO THE STANLEY WORKS, OF NEW BRITAIN, CONNECTICUT, A CORPORATION OF CONNECTICUT.

FOLDING RULE.

Application filed July 23, 1921. Serial No. 428,091.

To all whom it may concern:

Be it known that I, WALTER H. HART, a citizen of the United States, and a resident of New Britain, county of Hartford, State 5 of Connecticut, have invented certain new and useful Improvements in Folding Rules, of which the following is a specification.

This invention relates to folding rules of the type having a plurality of sections pivotally connected together at their overlapping ends so that they may be folded one over the other into compact space when not in use, and swung into extended relation when it is desired to use the rule for measuring or other purpose.

The aim of the present invention is to provide a device of this sort having various features of novelty and advantage, and which is particularly characterized by its 20 extreme simplicity in construction and therefore economy in manufacture; by its relative lightness in weight and its compactness when folded up so that it may be conveniently carried about; and by its effectiveness in operation in that the contiguous sections, when extended, are firmly maintained in proper alined relation and the rule, as a whole, is sufficiently stiff in spite of its lightness in weight, to be conveniently 25 handled in taking measurements, etc.

To these ends the present invention contemplates a folding rule made up of a plurality of relatively thin strips of metal, preferably of a springy or resilient nature, 35 such as thin resilient steel; these strips or sections are provided with longitudinally extending corrugations to impart requisite stiffness to the rule; and the sections are connected together in a very simple, practical and effective manner, preferably, the 40 resiliency of the metal forming the sections and the stiffening corrugations being taken advantage of for frictionally holding and firmly locking the parts in alinement with 45 each other when these parts are in either folded up or in extended positions.

In the accompanying drawings, wherein I have shown for illustrative purposes one embodiment which the present invention 50 may take,

Fig. 1 is a view, slightly in perspective, showing several sections of the rule in partly extended relation,

Fig. 2 is an enlarged view showing, in

plan, the joint between two extended sections,

Fig. 3 is a sectional view taken on line 3—3 of Fig. 2, and

Fig. 4 is a view taken substantially on line 4—4 of Fig. 2.

Referring to the drawings in detail, *a*, *a*, designate the sections of the rule, each suitably graduated as shown along either or both of its edges, and *b*, *b*, denote the members, here shown as rivets.

In accordance with the present invention each of the sections *a* is formed of a relatively thin strip of metal of a springy or resilient nature, such as thin flexible steel, and each is longitudinally corrugated for 70 the purpose of imparting sufficient stiffness to the rule to permit ready handling thereof when the sections are extended, and these corrugations are so arranged as to constitute interlocking means for maintaining the 75 sections in proper relation.

In the present illustrative disclosure each section is corrugated along its longitudinal center or median line, as indicated by the numeral 10. The corrugation 10 in each 80 section terminates at like distance from the pivotal points *b* and extends under the overlapping ends of the contiguous sections.

At each end of each section is a corrugation 11. The corrugation 10 and the corrugations 11 of each strip may be considered as a single corrugation extending throughout the length of the strip but interrupted adjacent the pivotal points at like distance to either side thereof. The respective ends of 90 the corrugations 10, 11, form what may be termed transverse shoulders 12, 13, equally spaced from the pivotal point. In one manner of speaking, the groove formed by the corrugation in one section may be considered as a recess and the rib or bead formed by the corrugation in a contiguous section and which nests in that recess may be termed a projection. In the present instance, the longitudinally extending shoulders formed by the side edges of the corrugations are flat, but it is to be understood 95 that the arrangement and shape of the corrugations here illustrated and described are by way of exemplification only, and they 100 may be varied as desired.

In the present illustrative disclosure, the rivets hold the contiguous sections in en-

gagement with each other, separate springs or other means for this purpose being dispensed with; thus when the adjacent sections are turned one relative to the other the metal adjacent the area of the rivets will be flexed permitting the corrugations to ride into and out of (as the case may be) nesting or interlocking relation.

It will be seen that with the arrangement described a very simple, practical and effective rule is provided. The corrugations, in addition to serving as stiffening means for the sections, are arranged to nest in one another and thus constitute interlocking means for firmly holding the sections in alignment when these sections are extended or folded up; also the transverse shoulders formed by the ends of the corrugations are adapted to interengage and constitute means for taking the strain off of the rivets, in a direction longitudinally of the rule section, and for preventing relative longitudinal displacement of the sections in the event the rivets *b* or the edges of the perforations in the sections receiving these rivets become worn through the movement of opening and closing the sections.

It is of course obvious that my invention is susceptible of various modifications and changes which are within the spirit of the invention without departing from the scope of the following claims, it being understood that the present disclosure is by way of illustration only and it is not to be taken as restrictive of my conception.

I claim as my invention:

1. In a folding rule, rule sections jointed together, each section comprising a thin strip of resilient metal provided with a lengthwise extending stiffening corrugation having a transverse shoulder and extending throughout the greater portion of the dis-

tance between the pivots of each section, the corrugations of contiguous sections being arranged to nest with said shoulders in engagement with each other. 45

2. In a folding rule, rule sections jointed together, each section comprising a strip of metal provided with a longitudinal corrugation extending throughout the greater portion of the distance between the pivots of each section terminating at equal distances to each side of the pivotal point between contiguous sections. 50

3. In a folding rule, rule sections jointed together, each section comprising a thin strip of metal provided with a length-wise extending stiffening corrugation and a transverse shoulder on each side of each pivot, the corrugations and shoulders of contiguous sections being arranged to nest with each other. 55

4. In a folding rule, rule sections jointed together, each section comprising a thin strip of metal provided with a length-wise extending stiffening corrugation and a transverse shoulder on each side of each pivot, the corrugations and shoulders of contiguous sections being arranged to nest with each other, said sections being formed of resilient metal. 60 70

5. In a folding rule, rule sections, and means for pivotally connecting them, each section comprising a single strip of thin metal of substantially uniform thickness and having a lengthwise-extending stiffening corrugation extending throughout the greater portion of the distance between the pivots of each section, said sections having transverse shoulders struck up from said strips at equal distances from the pivot and arranged to maintain said sections against relative longitudinal movement. 75 80
